UNITED STATES PATENT OFFICE.

JOHN Q. SLYE, OF WASHINGTON, DISTRICT OF COLUMBIA, ASSIGNOR OF ONE-HALF TO
THOMAS LINCOLN LIPSETT, OF WASHINGTON, DISTRICT OF COLUMBIA.

FOLDABLE OR EXTENSIBLE CAR STEP.

1,407,592.

Specification of Letters Patent. Patented Feb. 21, 1922.

Application filed August 17, 1921. Serial No. 492,951.

To all whom it may concern:

Be it known that JOHN QUEEN SLYE, a citizen of the United States of America, residing at Washington, and District of Columbia, has invented a new and useful Foldable or Extensible Car Step, of which the following is a specification.

The present invention has for its purpose the provision of an improved foldable or extensible car step for railway and other cars, thereby obviating the use of the usual step box or stool.

It is realized that extensible or foldable car steps have been heretofore devised, but the majority of them, are either inferior in construction and will not stand the constant usage, or are too complicated for practical use. Many of them are not properly reinforced and also too difficult to operate. Others are in the way, when the usual or ordinary steps of the car are used; and some when in operative position, extend too far down to pass all platforms at stations, and others are not extensible far enough.

In view of these facts the present invention aims to provide an improved construction of foldable or extensible car step, wherein means are afforded for reinforcing the extensible step, when in operative position, in order to withstand the varying weights applied thereon, due to its constant use by the passengers.

Another purpose involves a reinforcing operative connection between the extensible or foldable step and an operating shaft, with its construction being such as to prevent said operative reinforcing connection from collapsing unnecessarily, when the step is extended. In other words it is the aim to provide an operative toggle link reinforcing connection between the operative shaft and the shaft and the step, with its pivotally connected parts arranged and disposed, whereby the toggle links cannot unnecessarily open and cause the step to collapse, when the weight of the passenger is applied thereon.

Still another purpose consists in the provision of reinforcing means secured to the extensible step proper, to reinforce the parts thereof, and also to afford connections with the collapsible toggle links, to insure rigidity and strength.

A further purpose embodies the provision of means for mounting certain of said toggle

links on the operating shaft, so that the links may move with the shaft, when movement is imparted thereto, so as to properly extend the step.

A still further purpose is the provision of means connecting the operating shaft and the hinge of the door of the vestibule of the car, whereby when the door is opened, the extensible step is extended.

Additionally it is the aim to provide a direct connection between the operating shaft and the hinge of the vestibule door, either in the form of a rigid shaft connected to the hinge by a universal joint, or in the form of a flexible shaft, thereby enabling the extensible step to operate quickly and in unison with the movement of the door.

Some of the steps heretofore devised have been operated by the vestibule door, but the connections are either more or less complicated, or weak and inferior in construction, or not at all positive, hence the present invention aims to avoid these defects, and provide a positive operative connection between the vestibule door and the operating shaft for the step.

While the design and construction at present illustrated and set forth is deemed preferable, it is obvious that as a result of a reduction of the invention to a more practical form for commercial purposes, the invention may be susceptible of changes, and the right to these changes is claimed, provided they are comprehended within the scope of what is claimed.

The invention comprises further features and combination of parts, as will be herein-after set forth, shown in the drawings and claimed.

In the drawings:

Figure 1 is a perspective view of one end of a Pullman coach or car, showing the improved extensible step applied thereto, and showing the connection between the step and the hinge of the door;

Figure 2 is a view in side elevation of one end of a Pullman coach or car, showing the extensible step applied, and more clearly illustrating the operative connection between the hinge of the vestibule door and the operating shaft;

Figure 3 is a perspective view of the observation end of a Pullman car or coach, also showing the extensible step as applied, and illustrating the means, whereby the gate of

the observation platform may extend or retract the step;

Figure 4 is a view in elevation of the side of the usual steps, with portions of the side broken away, and showing the extensible step applied, with the operative connections between the hinge of the vestibule door and the step as arranged on the side;

Figure 5 is a sectional view through a portion of one of the fixed steps, showing the extensible step applied and collapsed in full lines, and extended in dotted lines;

Figure 6 is a view in elevation of the rear of the steps, showing the construction of the operative reinforcing connections between the operating shaft and the extensible step;

Figure 7 is a detail sectional view showing the shaft 11 engaging the bearing 33, and showing how the links 35 are fastened thereto;

Figure 8 is a detail sectional view through the pivotal connection between one of the links 37 and the rib of one of the straps 22; and

Figure 9 is a detail view of a flexible shaft 51.

Referring to the drawings, 1 designates a conventional form of Pullman coach or car, which is provided with the usual vestibule door 2, hingedly mounted on the jamb as at 3. The hinge 3 of the door extends substantially the full length of the jamb, and certain leaves 4 thereof are movable with the door. These leaves 4 are also secured at 5 so as to move with the shaft, pin or rod 6 which passes through the sleeves of the leaves of the hinge. The lower end of the shaft, pin or rod 6 is connected by a suitable universal joint 7 to a shaft link 8, for operating the extensible step.

Extending from the vestibule of the car are the usual stationary steps 9, the side supports 10 of which have suitable bearings for an operating shaft 11, which is located 45 immediately to the rear of the lower fixed tread 12 of the stationary steps 9. This shaft 11 has a central rectangular portion 13 and cylindrical extensions 14. The extensible step 15 comprises the tread 16 and the rise 17. It will be noted that where the rise 17 of the extensible step connects with the tread 12 of the stationary steps, the adjacent edges of said parts are mitered or beveled as shown at 18.

In order to not only reinforce the tread 12 relatively to the lower rise of the stationary steps, but also reinforce the tread and rise 16 and 17 as well as hinging them together, metallic straps 19, 20, 21 and 22 are secured as shown to the lower rise of the stationary steps 9, the tread 12 and the rise and tread 17 and 16 of the extensible step. It will be noted that the straps 19 form integral parts with the straps 20, which are 60 in turn hingedly connected at 23 to the straps 65

21. The lower ends of the straps 21 extend under and in engagement with the bevel 24 of the lower portion of the rise 17. The straps 22 have extensions 26, which engage the bevel 25 of the tread 16, and said extensions 26 are hingedly connected as at 27 to those (which engage the bevel 24) of the straps 21, thereby hingedly connecting the tread 16 and rise 17.

The straps 22 have webs 28, which are extended as shown and have bearings for the connecting rod 29, the reduced ends 30 of which pass through the bearings of the extensions of the webs 28, and have nuts 31 threaded thereon, there being cotter pins 32 80 to prevent detachment of the nuts.

Where the straps 19 and 20 integrally unite, suitable bearings 33 are provided for the reception of the reduced ends 14 of the shaft 11. The shoulders 34, caused to be 85 formed by the reduced cylindrical portions 14 of the shaft 11 cooperate with the bearings 33 to prevent axial movement of the shaft or pin 11.

Toggle links 35 are mounted on the ends 90 of the rectangular portion 13 of the shaft or pin 11, and owing to this portion 13 being rectangular, the links 35 move with the shaft or pin. Suitable pins 36 engage through the links 35 and the shaft 11, to 95 prevent movement of the links longitudinally.

Toggle links 37 are pivotally mounted upon the reduced ends 30 of the shaft or rod 29 between the shoulders 38 (caused 100 to be formed by the reduced extensions 30) and the extensions of the webs 28.

The links 35 and 37 are pivotally united by the rod 39, the reduced ends 40 of which have their extremities swaged to provide 105 heads 41, thereby connecting the links 35 and 37 in order to provide a toggle joint.

The links 35 are provided with shoulders 42 adjacent their connections with the rod 39, to engage with the shoulders 43 which 110 project laterally of the links 37, thereby limiting the links 35 and 37 in their extended positions. It will be noted that the pivot rod 39 is arranged in a position relatively to the shaft or pin 11 and the rod or pin 29, 115 so that said shaft or pin 39 will become positioned to one side of the aligned centers of the shafts or pins 11 and 29, and owing to the provision of the shoulders 42 and 43 the links 35 and 37 are prevented from further movement when the links and the step are extended.

Movable with one of the cylindrical extensions 14 of the shaft or pin 11 is a bevel gear 44, which meshes with a bevel pinion 45 125 mounted upon the lower end of the shaft 8, which is mounted in suitable bearings 46 of one of the sides of the stationary steps.

Obviously when the door 2 is swung open, causing the hinged leaves 4 to move with the 130

door and the shaft or hinge pin 6, movement is imparted to the shaft 8, which in turn transmits movement to the shaft or pin 11, through the medium of the bevel gears 44 and 45, thereby moving the links of the toggle joint, and cause the tread and the rise 16 and 17 to assume their extended positions. The tread 16 when extended becomes positioned above the platform 47 equal to the height of a rise, so that a passenger may easily ascend or descend from the platform and the steps.

In Figure 3 the gate 48, which is equivalent to the vestibule door is mounted to move with the hinged shaft 49, on which the gate is mounted, and through the medium of the pin or shaft 49 (which is connected by the universal joint 50 with the shaft 5) the extensible step may be lowered, when the gate is opened.

It is obvious that a flexible shaft 51 as shown in Figure 9 may be substituted for the shaft 8, thereby eliminating the universal joint, and yet at the same time provide a positive connection.

By the provision of the toggle joint connecting the shaft 11 and the shaft or pin 29, and by means of the several straps 19, 20, 21 and 22, positive reinforcing operative connections are afforded between the stationary steps and the extensible step, such as will stand the varying weights, due to the passengers passing up and down the steps.

The shaft 8, whether it be in the form shown in Figure 1, or in the form of a flexible shaft as shown in Figure 3, it is obvious that it may be operated by any other suitable means, other than the opening and closing of the vestibule door, or the gate of the observation end of a Pullman car. For instance the shaft may be operated by a hand wheel or handle or any other suitable means, where there is no vestibule door or gate. In either case, however, the operating means may be manually actuated though not necessarily.

There have been various attempts to provide an extensible step for railway cars, but the most of them are cumbersome, including many parts which need to be special made, furthermore they are not applied in a practical way, and also the majority of them include many operating parts, to cause the step to extend.

The present invention includes folding means, so operable when extended, to constitute a self-lock against refolding, in combination with a positive lock drive connection with certain of the operable means to prevent the step from refolding.

The constructions involved in the various attempts to provide an extensible step for railway coaches have been carefully studied, and as a result thereof the present construction of extensible step has been de-

vised. The present step is simple, practical and durable in construction, and positive in operation, emphasis being laid upon the fact that the shaft 11 is disposed in firm bearings, and through the medium of the links 35 and 37, which are self-lockable against refolding when the step is extended, the operating means for the step having a positive drive locking connection with the shaft in order to prevent accidental rotation of the shaft, between which and the step the links 35 and 37 constitute a positive reinforcement. Furthermore it will be noted that the operating drive means 8 is connected or geared with the shaft 11, and as long as this connection is maintained with the vestibule door open, there is not a possible chance for the links 35 and 37 to refold. It will be noted that the means to prevent refolding is not connected with the links near their pivot points, and then again the links are simply disposed between the rear of the stationary tread of the main steps and the rear of the extensible tread, to insure reinforcement.

The invention having been set forth, what is claimed as being useful is:

1. The combination with the vestibule car steps provided with an extensible and collapsible step, of an operating revoluble member located in bearings substantially to the rear of the lower tread of the vestibule car steps, means operatively connecting said revoluble member and the extensible and collapsible step, the construction and arrangement of said means being such as to rockably reinforce the tread of the extensible step relatively to the revoluble operating member, when the extensible step is extended.

2. The combination with the vestibule car steps provided with an extensible and collapsible step, of an operating revoluble member located in bearings substantially to the rear of the lower tread of the vestibule car steps, means operatively connecting said revoluble member and the extensible and collapsible step, the construction and arrangement of said means being such as to rockably reinforce the tread of the extensible step relatively to the revoluble operating member, when the extensible step is extended, and means manually actuated for rotating said rockable member to collapse the extensible step.

3. The combination with the vestibule car steps, of an extensible and collapsible step operatively mounted on the lower tread of said car steps, a revoluble operating member mounted in bearings of the sides of the car steps immediately adjacent the rear of the lower tread of the car steps, a toggle joint operatively connecting said revoluble operating member and the tread of the extensible step, whereby upon rotating said member the extensible step may be extended, the con-

- struction and arrangement of the form of pivot connecting the links of said toggle joint being such with relation to the connections of the links and the extensible tread and the operating member as to assume a position to one side of the centers of the connections of the links and the member and the extensible tread, thereby reinforcing the tread in its extended position.
10. 4. The combination with the vestibule car steps, of an extensible and collapsible step operatively mounted on the lower tread of said car steps, a revolute operating member mounted in bearings of the sides of the car steps immediately adjacent the rear of the lower tread of the car steps, a toggle joint operatively connecting said revolute operating member and the tread of the extensible step, whereby upon rotating said member the extensible step may be extended, the construction and arrangement of the form of pivot connecting the links of said toggle joint being such with relation to the connections of the links and the extensible tread and the operating member as to assume a position to one side of the centers of the connections of the links and the member and the extensible tread, thereby reinforcing the tread in its extended position, and abutment means carried by the links of the toggle joint to limit said pivot in such position.
15. 5. The combination with the vestibule car steps, of an extensible and collapsible step operatively mounted on the lower tread of said car steps, a revolute operating member mounted in bearings of the sides of the car steps immediately adjacent the rear of the lower tread of the car steps, a toggle joint operatively connecting said revolute operating member and the tread of the extensible step, whereby upon rotating said member the extensible step may be extended, the construction and arrangement of the form of pivot connecting the links of said toggle joint being such with relation to the connections of the links and the extensible tread and the operating member as to assume a position to one side of the centers of the connections of the links and the member and the extensible tread, thereby reinforcing the tread in its extended position, and abutment means carried by the links of the toggle joint to limit said pivot in such position.
20. 6. The combination with the vestibule car steps, of an extensible step comprising a hingedly united rise and tread, the rise thereof being hingedly united to the lower tread of the car steps, a revolute operating member journaled immediately to the rear of the lower tread of the car steps, and toggle joints having certain of the links fixed to the revolute operating member, and others pivotally united to the extensible tread, the construction and arrangement of the pivots connecting the links of the toggle joints relatively to the revolute member and the pivots to certain of the links and the extensible tread being such as to collapse on one side of the aligned centers of the revolute member and the pivots and the extensible tread, whereby the toggle joints may reinforce the extensible tread in an extended position, the pivoted ends of the links of the toggle joints having means to limit said links in their extended positions.
25. 7. The combination with the vestibule car steps, of an extensible step comprising a hingedly united rise and tread, the rise thereof being hingedly united to the lower tread of the car steps, a revolute operating member journaled immediately to the rear of the lower tread of the car steps, and toggle joints having certain of the links fixed to the revolute operating member, and others pivotally united to the extensible tread, the construction and arrangement of the pivots connecting the links of the toggle joints relatively to the revolute member and the pivots to certain of the links and the extensible tread being such as to collapse on one side of the aligned centers of the revolute member and the pivots and the extensible tread, whereby the toggle joints may reinforce the extensible tread in an extended position, the pivoted ends of the links of the toggle joints having means to limit said links in their extended positions, and means operatively connecting with the member for rotating the same for extending and collapsing the extensible step.
30. 8. The combination with the vestibule car steps, of an extensible step comprising a hingedly united rise and tread, the rise thereof being hingedly united to the lower tread of the car steps, a revolute operating member journaled immediately to the rear of the lower tread of the car steps, and toggle joints having certain of the links fixed to the revolute operating member, and others pivotally united to the extensible tread, the construction and arrangement of the pivots connecting the links of the toggle joints relatively to the revolute member and the pivots to certain of the links and the extensible tread being such as to collapse on one side of the aligned centers of the revolute member and the pivots and the extensible tread, whereby the toggle joints may reinforce the extensible tread in an extended position, the pivoted ends of the links of the toggle joints having means to limit said links in their extended positions, and means manually actuated and operatively connected to the member for rotating the same.
35. 9. The combination with the vestibule car steps, of an extensible step comprising a hingedly united rise and tread, the rise thereof being hingedly united to the lower tread of the car steps, a revolute operating member journaled immediately to the rear of the lower tread of the car steps, and toggle joints having certain of the links fixed to the revolute operating member, and others pivotally united to the extensible tread, the construction and arrangement of the pivots connecting the links of the toggle joints relatively to the revolute member and the pivots to certain of the links and the extensible tread being such as to collapse on one side of the aligned centers of the revolute member and the pivots and the extensible tread, whereby the toggle joints may reinforce the extensible tread in an extended position, the pivoted ends of the links of the toggle joints having means to limit said links in their extended positions, the construction and arrangement of the hinge connection connecting the extensible rise and tread relative to the pivots of certain links to the extensible

tread being such that when the links are collapsed the extensible tread is held in a raised collapsed position.

9. The combination with the vestibule car 5 steps, of an extensible step comprising a hingedly united rise and tread, the rise thereof being hingedly united to the lower tread of the car steps, a revolute operating member journaled immediately to the rear of the 10 lower tread of the car steps, and toggle joints having certain of their links fixed to the revolute operating member, and others pivotally united to the extensible tread, the 15 construction and arrangement of the pivots connecting the links of the toggle joints relatively to the revolute member and the pivots to certain of the links and the extensible tread being such as to collapse on one side of the aligned centers of the revolute member 20 and the pivots and the extensible tread, whereby the toggle joints may reinforce the extensible tread in an extended position, the pivoted ends of the links of the toggle joints having means to limit said links in their extended 25 positions, and means operatively connecting with the member for rotating the same for extending and collapsing the extensible step, the construction and arrangement of the hinge connection connecting the extensible 30 rise and tread relative to the pivots of certain links to the extensible tread being such that when the links are collapsed the extensible tread is held in a raised collapsed position.

35 10. The combination with the vestibule car steps, of an extensible step comprising a hingedly united rise and tread, the rise thereof being hingedly united to the lower tread of the car steps, a revolute operating member 40 journaled immediately to the rear of the lower tread of the car steps, and toggle joints having certain of their links fixed to the revolute operating member, and others pivotally united to the extensible tread, the construction and arrangement of the pivots connecting the links of the toggle joints relatively to the revolute member and the pivots to certain of the links and the extensible tread being such as to collapse on 45 one side of the aligned centers of the revolute member and the pivots and the extensible tread, whereby the toggle joints may reinforce the extensible tread in an extended position, the pivoted ends of the links of the toggle joints having means to limit said links in their extended 50 positions, the construction and arrangement of the hinge connection connecting the extensible rise and tread relative to the pivots of certain links to the extensible tread being such that when the links are collapsed the extensible tread is held in a raised collapsed position, the extensible rise and tread having abutting means, cooperating with the reinforcing toggle joints.

gle joints, to insure reinforcing the rise and 65 tread of the extensible step, when in extended position.

11. The combination with the vestibule car steps, of an extensible step comprising a hingedly united rise and tread, the rise 70 thereof being hingedly united to the lower tread of the car steps, a revolute operating member journaled immediately to the rear of the lower tread of the car steps, and toggle joints having certain of their links fixed 75 to the revolute operating member, and others pivotally united to the extensible tread, the construction and arrangement of the pivots connecting the links of the toggle joints relatively to the revolute member 80 and the pivots to certain of the links and the extensible tread being such as to collapse on one side of the aligned centers of the revolute member and the pivots and the extensible tread, whereby the toggle joints 85 may reinforce the extensible tread in an extended position, the pivoted ends of the links of the toggle joints having means to limit said links in their extended positions, the construction and arrangement of the 90 hinge connection connecting the extensible rise and tread relative to the pivots of certain links to the extensible tread being such that when the links are collapsed the extensible tread is held in a raised collapsed 95 position, the extensible rise and tread having abutting means, cooperating with the reinforcing toggle joints, to insure reinforcing the rise and tread of the extensible step, when in extended position, the vestibule 100 having a door, and means operatively connecting the vestibule door and the revolute operating member, for rotating the same.

12. The combination with the vestibule car steps, of an extensible step comprising 105 a rise and a tread provided with abutting means to support the tread in position when the rise is extended, a revolute operating member mounted in the sides of the car steps to the rear of the lower tread of the car steps, means operatively connecting said member and the tread for extending the extensible step, the construction and arrangement of said means being such as to reinforce the tread relatively to the member, a 110 vestibule door, and means operatively connecting the door and the revolute member.

13. In a device for the purpose indicated, vestibule car steps provided with an extensible and collapsible step, foldable means to 115 extend the extensible step, and when extended to constitute a self-reinforcement, an operating member for said foldable means, and means having positive drive and lock connections with said member.

14. In a device for the purpose indicated, vestibule car steps provided with an extensible and collapsible step, a pair of foldable

means connected to and for extending the step, and when extended to constitute a self-reinforcement for the step, means connecting said pair of foldable means to cause them to work in unison, an operating member, to which corresponding parts of both pairs of means are connected, and actuating means provided with a drive locking connection with one end of said member to prevent refolding of said pair of means.

15. The combination with the vestibule car steps provided with an extensible and collapsible step, of foldable operable means therefor, disposed, when extended, to constitute a self-lock against refolding, and means having a positive lock connection with said foldable means to insure against refolding.

16. The combination with the vestibule car steps provided with an extensible and collapsible step, of foldable members arranged in pivoted pairs, disposed when extended to constitute a self-lock against refolding, means connecting said pairs of members to cause them to fold and open in unison, and means provided with positive lock drive

connections with certain of said members to insure them against refolding.

17. The combination with the vestibule car steps provided with an extensible and collapsible step, of foldable members arranged in pivoted pairs, disposed when extended to constitute a self-lock against refolding, means connecting said pairs of members to cause them to fold and open in unison, a rotating element, and means having a positive locking drive connection with said rotating element, to insure the links against refolding.

18. The combination with the vestibule car steps provided with an extensible and collapsible step, of foldable operable reinforced means therefor at the rear of the extensible step, disposed, when extended, to constitute a positive reinforced self-lock against refolding.

45 In witness whereof, in the presence of two witnesses, the inventor's signature is hereunto affixed.
